(57) **CLAIM**

The ornamental design for a mobile phone with graphical user interface, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a mobile phone with graphical user interface; and,

FIG. 2 is a front view of the mobile phone with graphical user interface of FIG. 1.

The broken line drawing of a mobile phone is for illustrative purpose only and forms no part of the claimed design.

The Facebook trademark or mark in the right portion of the Figures is a registered trademark or the property of Facebook, Inc. The Twitter trademark or mark in the right portion of the Figures is a registered trademark or the property of Twitter, Inc. Trademarks are the property of their respective owners.

1 Claim, 2 Drawing Sheets
(2 of 2 Drawing Sheet(s) Filed in Color)

FIG. 1

FIG. 2
